UNITED STATES PATENT OFFICE.

WALTER P. MURPHY, OF CHICAGO, ILLINOIS.

RELEASE-RIGGING.

1,095,588.

Specification of Letters Patent.

Patented May 5, 1914.

Application filed December 27, 1913. Serial No. 809,028.

To all whom it may concern:

Be it known that I, WALTER P. MURPHY, a citizen of the United States, residing at Chicago, in the county of Cook and State 5 of Illinois, have invented certain new and useful Improvements in Release-Rigging, of which the following is a specification.

The object of my invention is to provide a release rigging that can be operated by 10 the brakeman while standing on the side step of the car by a movement of his foot in a vertical plane or in an arc, the vertical plane movement being especially adapted for one standing on the step because there is no 15 liability of his losing his balance and falling between or beneath the cars; and with these and other objects in view my invention consists of the parts and combination of parts as will be more fully hereinafter 20 pointed out.

In the drawings:—Figure 1 is a perspective view of a release rigging embodying my invention detached from the car; Fig. 2 is a top plan view of my improved release 25 rigging attached to the end sill of a car, parts of the car being in section; Fig. 3 is a detail end view of the same; Fig. 4 is an end view of a car with my release rigging attached, the car body being broken away; 30 Fig. 5 is a detail sectional view of Fig. 4 looking toward the right. Figs. 6 and 7 are top plan and front elevations, respectively, showing my lever adapted to bottom operating couplers.

35 The reference numeral 1 designates the car body, 2 the end sill, 3 the "deadwood" and 4 the draw bar and coupler having the locking pin 5.

The horizontal shaft 6 is revolvably mounted 40 on the end sill of the car in suitable brackets 7 which are secured to the end sill, the shaft being locked in said brackets by any suitable means, such for instance, as cotter pins 3. Any other suitable bracket may 45 be used. The outer end of the shaft 6 is bent at an angle or offset as at 9 to form a stop to limit the longitudinal movement of the shaft, while the inner end of the shaft has a crank arm 10 having its end rebent 50 to form an eye 11 through which the link 12 passes and has a flexible engagement therewith. The eye 11 is preferably an elongated eye while the upper portion 13 of the link 12 is preferably flat and has an open 55 hook 14 at its upper end. The lower end of the link 12 has a hook which engages the

eye of the locking pin 5. The construction of the upper part of the link and the eye is such that it constitutes a very flexible connection between the crank 10 and the coupler to accommodate the movements of the draw bar. The shaft 6 formed between its ends with an open rebend set at a suitable angle (say about 20 degrees) constitutes a crank 15 which I preferably incline toward 60 the end sill of the car. This crank 15, it will be noted is between the brackets 7 which position I now believe to be preferable. While I have stated that the crank 15 is placed at about 20 degrees, and while I have 65 found from actual experience that this angle is the proper one for present conditions in railroad construction I reserve the right to vary this angle to meet conditions as they may arise.

70 16 is the operating handle which depends below the plane of the underface of the end sill in compliance with the "safety appliance law."

75 17 is a crank projecting from the lower end of the handle 16 outwardly at right angles to the vertical plane of the end of the end sill, there being sufficient space between the crank 17 and the underface of the sill to enable the brakeman, standing on the 80 usual side step of the car, to place his foot on said crank and move the handle downward or swing it in an arc as will be hereinafter explained. The upper end of the handle is formed with an open rebend 18 85 which is constructed to flexibly engage the crank 15, whereby the handle is suspended from the shaft 6; the handle is then bent at substantially right angles to the rebend 18 90 forwardly with and slightly rearwardly 95 from the shaft 6 to form an arm 19 and is then bent forwardly at an angle and formed into an eye 20 constructed to receive the shaft 6, and constitutes the second point of bearing of the handle on the shaft 6, the 100 crank 15 being the other point of bearing for the handle of the shaft. It will be noted that the arm 19 is transverse of the crank 15. These two bearing points of the handle on the shaft are, as will be seen, both intermediate the ends of the shaft. I shall, for 105 the sake of brevity in the claims, refer to the parts 16 and 17 as the handle or the operating handle.

110 The parts being properly assembled, the brakeman, standing on the side step of the car, may raise the locking pin 5 by either

pushing downward with his foot on the handle, or by swinging the handle in an arc as found most convenient to him. When the handle is pushed downwardly in a vertical 5 plane it pulls downward on the crank 15, thereby revolving the shaft 6, thus moving the crank 10 upward and lifting the locking pin 5. When the handle is swung forward in an arc the rebend 18, by reason of 10 the portion 19 interlocks with the crank 15, thereby revolving the shaft 6 and unlocks the pin 5.

While I speak of the shaft 6 as a "horizontal" shaft, it will be understood that I 15 do not wish to limit myself by this word to placing the shaft in a perfect horizontal position, although this position is undoubtedly the best, but it is sometimes advisable to have one end of the shaft higher than the 20 other due to some peculiar construction of a car to which it is attached.

In Figs. 6 and 7, I have shown an adaptation of my improved rigging for bottom operating couplers in which 21 is a bracket secured to the car in which the rock shaft 22 is journaled at its outer end. The bracket 21 is provided with a stop 23 against which the end 24 of the rock shaft rests so as to hold the pin lever in proper position relative to 25 the coupler, in case the hand lever should become bent in some manner. I do not herein claim this particular form of bracket provided with a stop as it will be claimed in another application. The inner end of the 30 rock shaft is journaled in a bracket 25 which is secured to a hanger 26 which in turn is secured to the underframe of the car. 27 is the draw bar. The inner end of the rock shaft terminates in a crank 28 with which the 35 locking pin lifting lever 29 has a flexible connection.

What I claim is:—

1. In a release rigging for a car coupler, a horizontally rotatable shaft having one 45 end operatively connected to the locking pin of the car coupler, an offset on said shaft intermediate its ends and an operating handle pivoted on said offset and also engaging said offset intermediate its end and said

shaft and having engagement with said shaft beyond said offset, whereby the shaft is rotated by a vertical plane or an arcuate movement of said handle.

2. In a release rigging for a car coupler, a rock shaft flexibly connected with the coupler at its inner end, a crank on said shaft intermediate its ends, and an operating handle pivotally mounted on said crank, whereby the locking pin of the coupler is operated by a downward movement of the handle, 55 said handle also having an operative engagement with said crank intermediate its end and said shaft and having pivotal engagement with the said shaft whereby the locking pin is operated by an arcuate movement of the handle.

3. In a release rigging for a car coupler, a rock shaft flexibly connected with the coupler pin at one end, a crank formed on said shaft intermediate its ends by an open return bend, an operating handle pivotally connected with said crank, an arm extending forwardly from said handle beyond the crank substantially in the direction of the length of the shaft and having operative engagement with one arm of said crank and terminating in an eye loosely engaging said shaft.

4. In a release rigging for a car coupler, a rock shaft flexibly connected at its inner 80 end with the coupler pin, a crank formed on said shaft intermediate its ends, an operating handle engaging said crank, whereby the shaft is rotated by a downward push on said handle, an arm on said handle extending 85 transversely of and beyond the crank and deflecting rearwardly from the shaft and provided with an eye loosely engaging the shaft between the crank and the inner end of the shaft whereby the shaft is rotated 90 when the handle is rotated.

In testimony whereof I affix my signature in presence of two witnesses.

WALTER P. MURPHY.
